TURNING LATHE FOR MAKING BOWLS

Robert Irving, 123 Bruce Road, Walpole, Mass., and
William M. Irving, 573 Dover Road, Westwood, Mass.

Filed Nov. 3, 1958, Ser. No. 53,260

Term of patent 14 years

(Cl. D54—6)

Fig. 1

Fig. 2

FIG. 3

FIG. 4

Fig. 1 is a top plan view of a turning lathe for making bowls showing our new design;

Fig. 2 is a side elevational view thereof;

Fig. 3 is an end elevational view thereof; and

Fig. 4 is an elevational view thereof from the opposite end.

We claim:

The ornamental design for a turning lathe for making bowls, substantially as shown.
